UNITED STATES PATENT OFFICE.

STEPHEN G. SKINNER, OF CHICAGO, ILLINOIS.

AIR-PUMP.

1,327,783.

Specification of Letters Patent. Patented Jan. 13, 1920.

Application filed June 28, 1919. Serial No. 307,331.

To all whom it may concern:

Be it known that I, STEPHEN G. SKINNER, a citizen of the United States, residing at Chicago, in the county of Cook and State 5 of Illinois, have invented a certain new and useful Improvement in Air-Pumps, of which the following is a full, clear, concise, and exact description, reference being had to the accompanying drawings, forming a part 10 of this specification.

My invention relates to air pumps, particularly to that class of air pumps which are employed for inflating pneumatic tires, and briefly stated, the objects of my invention 15 are:

First: The provision of a pump of this class in which the piston and valve elements are so arranged that the pump is capable of rapidly performing its intended function 20 when properly operated, due to the fact that before each downward or compression stroke that portion of the pump cylinder below, or ahead, of the piston, is completely filled with air at atmospheric pressure;

Second: The provision of a pump of this class having a valved piston, the valve element of which is in the form of a flat disk of leather or similar material, which is entirely inclosed within and protected by the 25 other parts of the piston;

Third: The provision of a valved piston comprising an extremely small number of parts, which are capable of being easily and economically manufactured and assembled;

Fourth: The provision of a pump comprising a valved piston the metallic parts of which may be entirely of drawn or pressed metal; and

Fifth: The provision of a pump of this 40 class provided with a foot piece hingedly mounted on the pump base, which base is so formed that it co-operates to lock the foot piece in its "down" position.

These and other objects of my invention 45 are fully set forth in the following description, in which reference is made to the accompanying drawings, wherein—

Figure 1 is a vertical sectional view of my improved pump;

Fig. 2 is an enlarged vertical sectional view of the pump piston;

Fig. 3 is an isolated axial sectional view of the pressed metal member, which constitutes the top of the male element of the 55 piston;

Fig. 4 is a similar view of the pressed

metal member which constitutes the bottom of the male element of the piston;

Fig. 5 is a top plan view of the male element of the piston, with the upper and lower parts thereof assembled and secured together.

Fig. 6 is an axial sectional view of the pressed metal member which constitutes the female element of the piston;

Fig. 7 is a plan view of the under side of the part illustrated in Fig. 6; and

Fig. 8 is a sectional view taken on line 8—8 of Fig. 1, this view illustrating the several parts in substantially their normal 70 size.

Similar reference characters refer to similar parts throughout the several views.

Referring first to Fig. 1, the pump there shown comprises the tube or cylinder 10, the upper end of which is provided with a cap 11 apertured at 12. The lower end of the tube is screwthreaded or otherwise suitably secured in a cast metal base 13, which is suitably drilled and tapped, as shown, to provide a passage between the lower end of the tube and a nipple 14, which in turn is provided with the usual hose 15 adapted to be attached by a coupling 16 to the valve of a pneumatic tire. At 17 is illustrated the piston rod, which has a sliding fit in the cap 11, and is provided with an operating handle 18. As thus far described the parts shown are conventional, and may be of any suitable form.

At its lower end the piston rod is provided with a valved piston, the several parts of which are illustrated in detail in Figs. 2 to 7 inclusive. Briefly, this piston comprises four principal parts, to-wit, a male element, a female element, a leather cup washer, and a valve member in the form of a leather disk. The male element comprises two pressed metal members 19 and 20. The member 19 comprises a disk-like portion 19^a, from which is struck a hollow central boss 19^b, which is internally screwthreaded to receive the externally threaded lower end of the piston rod 17. An aperture 19^c is punched in the disk portion 19^a. The male member 20 is hollow, and comprises the externally threaded cylindrical portion 20^a closed at its lower end except for a central aperture 20^b. This member 20 is shouldered at 20^c to provide a support for the disk portion of member 19, and comprises a flange 20^d which embraces the disk portion of mem-

ber 19. The members 19 and 20 are secured together by pressing portions of the metal of flange 20^a down on the member 19 at a plurality of points 20^b, as is clearly shown 5 in Figs. 2 and 5.

The female element consists of a cylindrical pressed metal member 21, open at its upper end and internally threaded to receive the externally threaded lower end of the 10 male member 20. The bottom wall of the female element has a boss 21^a struck upwardly therefrom, forming an annular channel between the boss and the inner cylindrical surface of the female element. A plurality of 15 apertures 21^b, 21^c afford communication between said annular channel and the bottom of the female element.

Securely clamped between the male and 20 female elements 20 and 21 is a leather cup washer 22, there being an annular space 23 between the cup washer and the outer cylindrical surface of the female element. Loosely mounted in the chamber formed between the bottom of the female member 21 and the 25 lower end of the male member 20 is the valve element which is in the form of a leather disk 24, normally resting on the boss 21^a, said leather disk being of a diameter considerably less than the inner diameter of the female element 20.

In the operation of the pump, on the up stroke of the piston air enters the aperture 12 in the cylinder cap 11, and passes from the space above the piston to the space below 35 the piston. The air in passing from the space above the piston to the space below the piston may take two paths. Some of the air may pass around the outside of the downwardly facing cup washer 22. However, practically all of the air takes a path 40 which on the upward stroke of the piston is entirely unobstructed. The air passes through the aperture 19^c into the hollow male element of the piston, thence through aperture 20^b around the edges of the leather 45 valve member 24, which is resting in the position shown in Fig. 2, and out through the apertures 21^b. This unobstructed path insures that, prior to the beginning of the 50 downward stroke of the piston, the space below the piston shall be completely filled with air, making the operation of the pump extremely rapid. On the downward movement of the pump piston compression below 55 the piston causes the disk 24 to seat tightly against the bottom of the male member 20, effectually closing the aperture 20^b and preventing the escape of air under pressure through the piston. At the same time the 60 air under pressure filling the annular space 23 forces the cup washer tightly against the inner surface of the pump piston and prevents the escape of pressure around the piston.

65 The foot piece 25 is in the form of a sub-

stantially U-shaped bail of spring metal, the legs of which are turned inwardly at 26, 26 and engaged in a transverse bore 27 in the base 13. A pair of substantially horizontal shoulders 28 and 29 are formed integral 70 with the boss 13, there being a groove between these shoulders, as shown. When the bail or foot piece is moved from the raised position shown in dotted lines in Fig. 1 to the full line position, the ends of the 75 bail move outwardly, as indicated in dotted lines in Fig. 8, to permit the legs of the bail to pass over the shoulder 28 and snap into the groove between the shoulders 28 and 29. The foot piece is thus held in its "down" position until sufficient force is applied thereto to cause the legs of the bail to snap over the shoulder 28.

Having thus described my invention, what I claim as new and desire to secure by Letters Patent of the United States is:

1. In an air pump, the combination with a tube or cylinder exposed to the atmosphere at its upper end, a piston rod adapted to be reciprocated in said cylinder, threaded 90 at its lower end and there provided with a valved piston comprising a cup washer, and male and female elements between which said cup washer is clamped, said male element consisting of an apertured disk member having an internally screwthreaded upwardly projecting boss coöperating with the threaded lower end of the piston rod, an externally threaded hollow cylindrical member having a centrally apertured bottom 100 wall and an upper flange which embraces and is secured to the disk member, said female element comprising a hollow cylindrical member internally threaded to receive the externally threaded cylindrical 105 portion of the male element, and provided with a bottom wall having an upstanding central boss, an aperture in said last-mentioned bottom wall adjacent said last-mentioned boss, and a leather disk valve of less 110 diameter than the inside diameter of the female element, said disk valve being normally freely disposed on said last-mentioned boss, and adapted to close the aperture in the bottom of the male element when the 115 piston is on its down stroke.

2. In an air pump, the combination with a tube or cylinder exposed to the atmosphere at its upper end, a piston rod adapted to be reciprocated in said cylinder and provided 120 at its lower end with a valved piston, comprising a hollow externally threaded cylindrical male element and a hollow cylindrical internally threaded female element co-operating therewith, an annular shoulder on 125 the hollow male element, a downwardly facing cup washer clamped between said shoulder and the upper end of the female element, a centrally apertured bottom wall for said male element, a bottom wall for the 130

female element provided with a centrally disposed upstanding boss, an aperture in the bottom of the female element adjacent said boss, and a leather disk valve, the diameter 5 of which is less than the inner diameter of said female element, said disk valve being freely disposed between said bottom walls, normally resting on said upstanding boss and adapted to close the central aperture 10 in the bottom of said male element when the piston is on its down stroke.

3. In an air pump, the combination with a tube or cylinder exposed to the atmosphere at its upper end, a piston rod adapted to be 15 reciprocated in said cylinder and provided at its lower end with a valved piston comprising a downwardly facing cup washer and metal piston elements which provide two inclosed chambers with a centrally ap- 20 tured wall between them, a centrally disposed upstanding boss carried by the bottom wall of the lower chamber, an aperture in said last-mentioned wall, adjacent said boss, means permanently affording commu- 25 nication between the upper chamber and that portion of the cylinder above the piston, and a leather disk valve freely disposed in the lower chamber, said disk valve being normally disposed on said boss, but adapted 30 to close the central aperture in the wall be- tween said chambers when the piston is on its down stroke.

4. In an air pump, the combination with a tube or cylinder exposed to the atmosphere 35 at its upper end, a piston rod adapted to be reciprocated in said cylinder and provided

at its lower end with a valved piston comprising a downwardly facing cup washer and metal piston parts providing an in- 40 closed chamber, a central aperture in the top wall of said chamber, through which communication with the atmosphere is es- tablished, an upstanding central boss carried by the bottom wall of said chamber, an aperture in said bottom wall adjacent said 45 disk, and a leather disk valve freely dis- posed in said chamber, normally resting on said upstanding boss, but adapted during the downward movement of the piston to close the aperture in the upper wall of said 50 chamber.

5. An air pump comprising a cylinder, a piston adapted to be reciprocated in said cylinder, a base in which the lower end of said cylinder is secured, a bore in said base 55 on one side of said cylinder, a foot piece in the form of a U-shaped bail of spring metal, having inturned ends engaging in said transverse bore, together with upper and lower horizontal shoulders formed on the 60 sides of said base, providing between them a depression into which the legs of said U-shaped bail member snap when the bail is moved into a plane parallel with the bottom 65 of the base.

In witness whereof, I hereunto subscribe my name this 26th day of June, 1919.
